SKIRT HANGER

Samuel L. Rubin, Chicago, Ill.

Application July 21, 1950, Serial No. 175,035

3 Claims. (Cl. 223—95)

1

The present invention relates to a skirt hanger, and is concerned primarily with a skirt hanger which is effective to maintain a skirt in stretched or taut condition without requiring the use of any hooks, pins or clamps.

At the present time members of the feminine sex are desirous of hanging the skirts which they wear in a condition in which all wrinkles are substantially avoided. Moreover, they are equally desirous of placing a skirt on a hanger and taking it off a hanger with a minimum of inconvenience.

With the foregoing conditions in mind the present invention has in view as its foremost objective the provision of a skirt hanger which will fulfill these requirements. More in detail the invention has as an object the provision of a skirt hanger which consists essentially of a horizontal bar from the mid-point of which upstands a vertical rod that is formed at its upper end with a hook, and a pair of tubular sleeves slidably mounted on the crossbar on the opposite sides of its mid-point. Another tubular sleeve that is fairly heavy in weight is slidably mounted on the vertical bar. A link connects each sleeve on the crossbar with the sleeve on the vertical bar. Each sleeve on the crossbar is provided with a member having a ribbed or serrated surface which is adapted to engage within the waistband of a skirt.

Under normal conditions the weight of the tubular sleeve on the vertical bar exhibits a tendency to cause this member to fall downwardly under gravity action. This tendency is transmitted through the links to the sleeves on the crossbar to cause them to move outwardly. When the ribbed members are inserted within a waistband of a skirt this tendency of the sleeves on the crossbar to move outwardly will maintain this waistband in a taut or stretched condition, and at the same time support the weight of the skirt.

Obviously, the skirt may be positioned or removed from the hanger with a minimum of inconvenience. To position the skirt on the hanger all that is necessary is to move the link on the vertical rod upwardly a sufficient distance to draw the sleeves on the crossbar inwardly so that the ribbed members carried thereby may be inserted within the waistband of a skirt. Upon release of the sleeve on the vertical bar the latter will fall downwardly under gravity action to cause the skirt to be held by the hanger. The release is even more simple. All that is required is to move the sleeve on the vertical bar up-

2

wardly to withdraw the sleeves on the crossbar inwardly, and thereby release the skirt.

Various other detailed objects and advantages of the invention such as arise in connection with carrying out the above noted ideas in a practical embodiment will, in part become apparent, and in part be hereinafter stated as the description of the invention proceeds.

The invention therefore comprises a skirt hanger which consists essentially of a crossbar having a vertical rod upstanding from its mid-point and formed at its upper free end with a hook. A fairly heavy sleeve is slidably mounted on this vertical rod while a pair of sleeves are slidably mounted on the crossbar on the opposite sides of its mid-point. A link connects each of the latter sleeves with the sleeve on the vertical rod. Each of the sleeves on the crossbar carries a ribbed member that is adapted to engage within the waistband of a skirt.

For a full and more complete understanding of the invention reference may be had to the following description and accompanying drawing wherein:

25 Figure 1 is a view in front elevation of a skirt hanger designed in accordance with the precepts of this invention and shown with the skirt applied thereto with the skirt being represented in phantom outline.

30 Figure 2 is a detailed vertical section taken about on the plane represented by the line 2—2 in Figure 1.

Figure 3 is a detailed vertical section taken about on the plane represented by the line 3—3 in Figure 1.

35 Referring now to the drawing wherein like reference characters denote corresponding parts the skirt hanger of this invention is shown as comprising a crossbar 10 and a vertical rod 11. 40 The rod 11 is secured to the crossbar 10 substantially at its mid-point and this connection may be effected by a T-coupling member 12 which is pinned to the crossbar 10 as depicted at 13. The upper end of the vertical rod 11 is formed with a hook 14 which preferably is an integral part thereof.

45 Slidably mounted on the vertical rod 11 is a sleeve 15 which is fairly massive and heavy, and which is formed with outstanding ears 16 and 17.

50 A sleeve 18 is mounted on the crossbar 10 at one side of the T-coupling member 12, and this sleeve 18 is formed with an ear 19 and carries a depending ribbed or serrated member 20. Another sleeve 21 is mounted on the crossbar 10 on the other side of the T-coupling member 12,

and this sleeve 21 is formed with an ear 22, and carries a depending ribbed or serrated member 23.

A link 24 connects the sleeve 18 to the sleeve 15. This is accomplished by a pivotal connection at 25 between the lower end of the link and the ear 19, and another pivotal connection at 26 between the upper end of the link 24 and the ear 16.

Likewise, a link 27 connects the sleeve 21 to the sleeve 15. This is accomplished by a pivotal connection at 28 between the lower end of the link 27 and the ear 22, and another pivotal connection at 29 between the upper end of the link 27 and the ear 17.

A skirt is represented in phantom outline in Figure 1, and is identified by the reference character S. Every skirt S which is to be supported from a hanger will ordinarily include a waistband. When the skirt S is to be supported the sleeve 15 is first moved upwardly on the vertical rod 11. This motion is transmitted through the links 24 and 27 to the sleeves 18 and 21 to draw the latter inwardly. The ribbed members 20 and 23 are now inserted within the waistband of the skirt. Upon release of the sleeve 15, the latter will move downwardly under the influence of gravity action, and cause the sleeves 18 and 21 carried thereby to move outwardly. This stretches the waistband into a taut condition, and the same action holds the skirt on the members 20 and 23.

To release the skirt all that is necessary is to again remove the sleeve 15 upwardly. This causes an inward movement of the sleeves 18 and 21, and the ribbed members 20 and 23 carried thereby, and permits the skirt S to be withdrawn therefrom.

While a preferred specific embodiment of the invention is hereinbefore set forth, it is to be clearly understood that the invention is not to be limited to the exact constructions, mechanisms, and devices illustrated and described, because various modifications of these details may be provided in putting the invention into practice within the purview of the appended claims.

What is claimed is:

1. A skirt hanger of the character described comprising a crossbar, a rod connected to said crossbar substantially at the mid-point thereof and arranged substantially normal thereto, a pair of sleeves slidably mounted on said crossbar on opposite sides of the mid-point thereof, a skirt

engaging member carried by each of said sleeves, another sleeve slidably mounted on said rod, and a pair of links connecting said last mentioned sleeve to the sleeves on said crossbar, there being a pivotable connection between each end of each link and the respective sleeve to which that end is connected.

2. A skirt hanger of the character described comprising a crossbar, a rod connected to said crossbar substantially at the mid-point thereof and arranged substantially normal thereto, a hook on the free end of said rod, a pair of sleeves slidably mounted on said crossbar on opposite sides of the mid-point thereof, a skirt engaging member carried by each of said sleeves, another sleeve slidably mounted on said rod, and a pair of links connecting said last mentioned sleeve to the sleeves on said crossbar, each of said links having one end pivotally connected to a sleeve on the crossbar and its other end pivotally connected to the sleeve on said rod.

3. A skirt hanger of the character described comprising a crossbar, a T-coupling member on said crossbar substantially at the mid-point thereof, a vertical rod having one end secured to said T-coupling and its other end formed with a hook as an integral part thereof, a sleeve slidably mounted on said vertical rod and having ears outstanding from the opposite sides thereof, a pair of sleeves slidably mounted on said crossbar on opposite sides of said T-coupling with each of said last mentioned sleeves having an upstanding ear and a downwardly depending ribbed skirt engaging member, and a pair of links, each of said links having one end pivotally connected to the upstanding ear on one of the sleeves on the crossbar and the other end pivotally connected to one of the outstanding ears on the sleeve on said vertical rod.
